(21) Appl. No.: **29/257,154**

(57) **CLAIM**

(22) Filed: **Mar. 30, 2006**

The ornamental design for an enclosure for portable electronic equipment, as shown.

(30) **Foreign Application Priority Data**

Oct. 10, 2005 (EM) 000413463

DESCRIPTION

(51) **LOC (8) Cl.** **03-01**

FIG. 1 is a top, side and front perspective view of the first embodiment of the enclosure for portable electronic equipment of the present invention;

(52) **U.S. Cl.** **D3/201; D3/218**

FIG. 2 is a bottom, opposite side, and rear perspective view thereof;

(58) **Field of Classification Search** D3/201,
D3/218, 215, 226, 269, 272–273; 206/305,
206/320; 455/90, 92, 42; 379/455; 224/901,
224/904, 682–683; D14/496, 156, 138

FIG. 3 is a top, side and front perspective view of the second embodiment; and,

See application file for complete search history.

FIG. 4 is a bottom, opposite side, and rear perspective view thereof.
